Primary Examiner — George D. Kirschbaum*Assistant Examiner* — Suzanne E Tisdell(57) **CLAIM**

The ornamental design for trunk cover or gate, as shown and described.

DESCRIPTION

FIG. 1 is a front perspective view of a trunk cover or gate on a vehicle;

FIG. 2 is an enlarged view of the portion of FIG. 1 depicting the trunk cover or gate;

FIG. 3 is a front orthogonal view of the trunk cover or gate; and,

FIG. 4 is a side orthogonal view of the trunk cover or gate. The broken lines present in the drawings are included for the purpose of illustrating portions of the article which form no part of the claimed design.

1 Claim, 4 Drawing Sheets(56)
